HOLDER FOR A BEDREADER

Norman R. Lykes, Scottsdale, Ariz.

Application November 18, 1957, Serial No. 697,033

1 Claim. (Cl. 248—166)

2

book overhead, page turning is achieved by pulling down page retainer 13, turning the page, and then replacing the bar approximately across the middle of the pages.

When placing a book or magazine on the holder, the horizontal retainer 13 may rest against pegs 11. The band 14 is prevented from slipping off the holder 9 by pegs 12.

Adjustment of angle or slant is permitted by friction hinge 8 in conjunction with cylindrical arm 7. This arm 10 may be attached to cross piece 3 by one of two means: When the holder is used as a bed reader or chair reader, the free end of hinged arm 7 is inserted into hole 22 of crosspiece 3. This is shown in Figure 2 where the book holder is drawn in broken lines and designated as 9a. When used as a music stand, portable lectern, or copy stand for typists as shown in Figures 2 and 4, the hinged arm 7 is placed against center fluted groove 19 and held in place by bolt and wingnut 17 through small hole 21 in crosspiece 3 and hole 23 near the end of hinged arm 7.

Hinged arm 7 could easily be rectangular, or triangular, or any other shape rather than cylindrical, and hole 22 similarly shaped to receive the arm.

Crosspiece 3 is secured at the desired height by J-bolt 5 pressing vertical cylindrical legs 1 into fluted grooves 20. The J-bolts are tightened by female threaded knobs 4. Large wingnuts could be used in place of knobs 4. The J-bolts also could be tightened by cam levers or other means.

Any of the three crosspiece grooves 19 and 20 could 30 just as well be triangular, or rectangular, or otherwise shaped instead of the cylindrical shape illustrated.

Legs 1 are maintained in a vertical position by nearly horizontal feet 2. Legs 1 and feet 2 are cross-notched and bolted. Foot 2 should originate out of leg 1 a few 35 inches from the bottom to allow for bumps or unevenness on a bed or blanket where the device might be used.

Figure 5 shows how the device's feet 2 may be turned inwardly so that it may be stored flat against a wall. Shelf 10 of bookholder 9 is hung over crosspiece 3.

40 What is claimed as new is as follows:

In a supporting structure for a book holding device, a pair of laterally spaced leg portions, said leg portions secured near their lower extremities to a pair of feet structures projecting outwardly, said leg portions adjustably secured to a single horizontal crosspiece structure 45 having a pair of laterally spaced vertical grooves against which said leg portions are clamped by means of threaded J-bolts and nuts through holes adjacent to said vertical grooves, said crosspiece portion approximately in its center having a third vertical groove and a plurality of holes 50 for receiving the hinged arm of a book holding device, said hinged arm secured to said supporting structure either by insertion of said arm through said crosspiece center hole, or by securing said arm vertically against said center vertical groove by means of a nut and bolt through 55 holes through said center vertical crosspiece groove and through said book holding device's hinged arm.
